UNITED STATES PATENT OFFICE.

JOHN ROGERS FLANNERY, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,409,162.

Specification of Letters Patent. Patented Mar. 14, 1922.

Application filed September 10, 1919. Serial No. 322,868.

To all whom it may concern:

Be it known that I, JOHN ROGERS FLANNERY, a citizen of the United States, and a resident of Pittsburgh, in the county of Allegheny and State of Pennsylvania, have invented certain new and useful Improvements in Stay-Bolt Structures; and I do hereby declare the following to be a full, clear, and exact description of the invention, such as will enable others skilled in the art to which it appertains to make and use the same.

This invention relates to improvements in staybolt structures for boilers,—one object of the invention being to provide a staybolt structure in which the staybolt and the closure for the opening in the boiler sheet shall be comprised in a single integral structure, and so that the closure portion of the device shall provide for endwise play of the bolt and still be united by welding to the boiler sheet.

With this and other objects in view, the invention consists in certain novel features of construction and combinations of parts as hereinafter set forth and pointed out in the claims.

In the accompanying drawings; Figure 1 is a sectional view, partly in elevation, showing an embodiment of my invention, and Figure 2 is a similar view showing another embodiment.

1 represents an outer boiler sheet and 2 the inner sheet of a boiler.

35 The outer boiler sheet is made with an opening 3, a portion of the wall of which may be made tapering and rounded to form a seat 4 on which the rounded head 5 at the outer end of a staybolt 6 has a mounting,—the inner end of said bolt being secured to the inner boiler sheet 2 in any suitable manner.

The staybolt may be made of steel and made integral with the headed end thereof, 45 in a spring cap or closure 7 which is so bent, as at 8, as to have sufficient spring or yielding action to permit proper longitudinal play of the staybolt. The peripheral portion of the cap or closure may be made in the form of a straight wall 8^a disposed at right angles to the boiler sheet 1 and having its lower edge engaging the latter.

A weld 9 surrounding the cap or closure 50 intimately unites the wall 9 of said cap or closure to the outer boiler sheet.

Centrally within the cap or closure and in the head of the staybolt, an angular recess or socket 10 is formed to receive a wrench, with the use of which the bolt may be screwed through the inner boiler sheet and, in the embodiment of the invention shown in Figure 1, a tell-tale hole 11 is made in the bolt and communicates with the recess or socket 10, the inner end of said tell-tale hole terminating below the neck portion of the bolt.

In the embodiment of the invention shown in Figure 2, the bolt is made with a tell-tale hole 12 which extends from the inner end of the bolt and terminates within the headed end thereof.

My improvements provide a one-piece flexible staybolt and closure and can be inspected either by the tell-tale hole or by the tapping method.

Having fully described my invention what I claim as new and desire to secure by Letters-Patent, is:

1. In a staybolt structure, the combination with a boiler sheet having an opening, of a staybolt having a head mounted on the wall of said opening, a cap or closure for said opening made integral with said head, said cap or closure having bent portions whereby the same will be yielding and said integral cap or closure having a peripheral portion seated on and disposed at right angles to the boiler sheet, and a weld surrounding said peripheral portion of the cap and uniting the latter to the boiler sheet.

2. In a staybolt structure, the combination with a boiler sheet having an opening formed to provide a seat for the head of a staybolt, of a staybolt having a head mounted on said seat and also provided with a yielding member integral with said head, said integral yielding member having a peripheral wall seated at its edge against the outer face of the boiler sheet, said peripheral wall of the yielding member being welded to the boiler sheet.

In testimony whereof, I have signed this specification in the presence of two subscribing witnesses.

JOHN ROGERS FLANNERY.

Witnesses:

JAMES R. HORAN,
EDWIN S. RYCE.
